UNITED STATES PATENT OFFICE

2,007,485

THREAD CUTTING DEVICE FOR
AUTOMATIC LOOMS

Kiichiro Toyoda, Nagoya, Japan

Application February 10, 1933, Serial No. 656,071

1 Claim. (Cl. 139—303)

This invention relates to a device for cutting the trailing threads near the selvage of the fabric upon the weft replenishing operation in an automatic loom.

5 In the hitherto known device employing a continuously moving cutter, there is a disadvantage that the cutting edge of the cutter is subjected to continuous wear so that it must be renewed frequently, since otherwise the cutter would fail to effectively sever the threads and the threads tend to wrap around the cutter. In order to prevent the cutter from being subjected to continuous wear, it has been proposed to provide a mechanism wherein the cutter acts only twice in 10 succession after the completion of the weft replenishing operation, so that it cuts the freshly inserted thread as well as the nearly spent thread. Irrespective of continuous or intermittent operation of the cutter, in the prior mechanisms, the cutter consisting of a blade or shears would after 15 all become ineffective by reason of the wearing down of the cutting edge thereof, and wrapping of the trailing thread would often take place, failing in completely cutting the threads.

20 The object of the present invention is to remove such disadvantages in existing devices by providing a novel construction of cutting mechanism which can be used effectively for a long time without necessitating renewal of the cutter.

25 Another object of the invention is to provide a cutting mechanism which is of very simple construction, requiring minimum adjusting portions.

In the drawing, illustrating what I now consider the preferred form of my invention,

30 Figure 1 is a sectional side view of certain parts of an automatic loom with my mechanism applied thereto, and

35 Figure 2 is a detail plan view in an enlarged scale.

40 Referring to the drawing, 1 is a slay sword, 2 the slay, 3 a reed cap, and 4 is a temple case on the loom frame. In said temple case 4 is provided a slot 5 close to the selvage of the fabric A. According to this invention, the cutter consists of a 45 hammer 6 and an anvil 7 formed by the bottom of said slot 5 in the temple case 4. The hammer 6 is pivoted at 8, and has a depending shank 9, the arrangement being such that the hammer proper 6 is normally held in the elevated position by the weight of the depending shank 9. The

front side of the slay 2 is fitted with a presser contact 10 which is adapted to engage with and press against the lower end of the depending shank 9 of the hammer when the slay 2 reaches the end of the forward movement.

5 When a weft replenishing operation, for instance, a shuttle exchange operation takes place, trailing threads of the spent and fresh shuttles pass through the space between the hammer 6 and the anvil 7 in the slot 5. As soon as the slay 2 reaches the end of the forward movement, the presser contact 10 impinges upon the lower end of the depending shank 9 of the hammer, so that the hammer proper 6 will suddenly turn downwardly and, co-operating with the anvil 7, cut 10 the trailing thread by blow. On experiments, I have found that the hammer succeeds in cutting the thread by a single blow. Assuming that the hammer should fail to completely sever the thread at the first blow, there would not be encountered any difficulty, since the hammer 6 acts continuously during the operation of the loom. On the other hand, regardless of the continuous movement, the cutting mechanism according to 15 this invention remains effective for a long time, 20 practically for the entire life of the loom, since the cutter has neither blade nor cutting edge 25 which requires to be renewed.

I have herein described the principle and operation of my invention, together with the device 30 which I now consider to represent the best embodiment thereof, but I desire to have it understood that the device shown is only illustrative and that the invention can be carried out by other means. For instance, any other mechanism may 35 be employed for actuating the hammer forming the cutter.

What I claim is:

In a loom, the combination with a temple case 40 and a slay, of a thread severing device, comprising a pivotally mounted hammer having a depending shank for normally holding the hammer head in elevated position, means provided on said slay for operating said hammer through said depending shank, and an anvil-formed bottom of a 45 slot in said temple-case for cooperating with said hammer.

KIICHIRO TOYODA.
